BAGGING MACHINE WITH HORIZONTALLY SWINGABLE BAG SPREADING FINGERS

Cecil Daniel Hughes, Winter Haven, Fla.

Application December 2, 1947, Serial No. 789,230

6 Claims. (Cl. 226—61)

1

This invention relates to a bagging machine and more particularly to an automatic machine for filling bags with fruit, for example, citrus fruits, vegetables, and the like.

An object of the invention is to provide an automatic bagging machine that requires a minimum of attention in operation. An operator is required to place the empty bags in the machine, but, thereafter, the bags are filled, closed, sewn, cut, and ejected from the machine without human intervention.

Another object is to provide a bagging machine having a device for holding the bags open and transporting them through the machine, which permits ready affixation of the bags thereto, which cooperates in the functioning of the article feeding mechanism to dispense articles into the bags, which coacts with related elements to effect closure of the mouths of the bags, and from which the bags may be readily removed by mechanical means.

Another object is to provide in a machine of this character improved devices for feeding articles in the nature of oranges or other fruit into the bags.

Another object is to provide an automatically actuated device for severing the thread that unites adjacent bags after the bags pass the sewing station and before they are ejected from the machine.

Another object is to provide an automatic machine of the class described that introduces a pre-selected number of fruit into each bag.

Still another object is to provide a machine of this character that is rugged and has a long service life relatively free from maintenance troubles.

In general, the bagging machine of the invention includes a horizontally disposed conveyor, means for driving the conveyor, and a bag supporting device carried by the conveyor comprising a pair of bag supporting elements dependently mounted on the conveyor for rotation about vertical axes, each of the elements having a pair of spaced leg members, means on the leg members adjacent to the lower ends thereof for holding a portion of the lip of a bag, the bag supporting elements being so spaced on said conveyor that the bag lip holding means define a substantially quadrangular figure when the bag supporting elements are disposed transversely to the direction of travel of the conveyor and define a line parallel to the line of travel of the conveyor when the bag supporting elements are rotated to a position parallel to the direction of travel of the conveyor.

2

In the following detailed description, two modifications of the bag supporting device are disclosed by way of illustration.

The bag supporting devices have members cooperating with the article feeding mechanism of the bagging machine for operating the mechanism to dispense articles into bags carried by the devices and the bagging machine includes track and cam members cooperating with the bag supporting devices for holding the mouths of bags open and for closing the mouths of bags carried by the bag supporting devices.

Specific forms of article feeding mechanisms are disclosed hereinafter in greater detail.

15 The principles of the invention will be set forth with greater particularity and other objects and advantages of the invention will be in part apparent and in part pointed out in the following detailed description taken in connection with the accompanying drawings, wherein:

Fig. 1 is a plan view of a bagging machine in accordance with the invention;

Fig. 2 is a somewhat enlarged left end view of the machine shown in Fig. 1;

25 Fig. 3 is a front view of the left-hand end of the machine on the same scale as Fig. 2;

Fig. 4 is a still further enlarged plan view of a portion of the machine adjacent to the bag filling station;

30 Fig. 5 is an enlarged sectional view taken along the plane of the line 5—5 of Fig. 1 showing details of an article feeding or dispensing device;

Fig. 6 is a partially sectioned left-hand view of the article dispensing device as shown in Fig. 5;

35 Fig. 7 is a detail side view of the article dispensing device illustrating the action thereof;

Fig. 8 is a detail plan view of a portion of the conveyor chain including a bag supporting device;

40 Fig. 9 is an elevational view of the device shown in Fig. 8;

Figs. 10 through 13 are side views with parts broken away of one of the elements of the bag supporting device;

45 Fig. 14 is a view corresponding to Fig. 5 of an alternative form of article dispensing device;

Fig. 15 is a fragmentary sectional view of a portion of a modified type of machine showing an alternative form of bag supporting element and mechanical means for tripping the article feeding mechanism;

Fig. 16 is a left-hand view of a portion of the apparatus shown in Fig. 15;

55 Fig. 17 is a view with parts broken away of a bag supporting element used in conjunction with the bag supporting element shown in Fig. 15 to

provide a complete device for supporting a bag; and

Fig. 18 is a right-hand view of the bag supporting element of Fig. 17.

Referring to the drawings, particularly to Figs. 1 through 3 thereof, the bagging machine shown has a driven sprocket wheel 20 and an idler sprocket wheel 21 supported by conventional bearings and framework for rotation on vertical shafts 22 and 23. Driving power for the sprocket wheel 20 is supplied by an electric motor 24 through a speed-reducing gear 25 to the shaft 22.

A continuous conveyor chain 26 is trained around the sprocket wheels 20 and 21 and carries a plurality of bag supporting devices 27-28 conveying bags from the bag attaching station or zone 29, around the idler wheel 21, through the bag filling zone 30 and the bag closing station 31, past the sewing machine 32, and the thread severing knife 33 to the bag removal station 34. The bag supporting devices are then returned by the conveyor chain around the driven wheel 20 to the bag attaching station 29.

One form of mechanism for feeding a predetermined number of oranges or other fruit to each bag will now be described with particular reference to Figs. 4 through 7. As seen in Fig. 4, the bags 35a, 35b, and 35c are carried through the filling zone 30 from right to left, the bags being supported with their open mouths facing upwardly to receive oranges.

Arranged on the outside of the conveyor chain is a series of parallel feeding chutes 36, each chute comprising a pair of downwardly inclined rails 37 spaced apart to support the oranges 38 for gravitational rolling movement down the chute and into the bags passing under the lower end of the chute. At the discharge end of each chute there is located a dispensing mechanism operative to dispense one orange at a time from the chute into a bag. The details of the dispensing mechanism will be described hereinafter with reference to Figs. 5 through 7.

On the inside of the conveyor chain there is located a series of electrical switches 39, shown in greater detail in Fig. 4, each switch corresponding to one of the dispensing mechanisms associated with the chutes. As shown in Fig. 5, circuit elements connect the switches with their corresponding dispensing mechanisms in such a manner that when each switch is closed and then opened, the dispensing mechanism associated therewith is operated to dispense one orange from a chute.

The switches are provided with operating slides 40 normally biased to open position but depressable to closed position by means of pins 41 carried by the elements 27 of the bag supporting devices 27-28 as the pins are dragged across the faces of the operating slides.

The switches and the switch operating pins are so related that an orange is dispensed from each chute when a bag is directly under the bottom of the chute and in position to receive the fruit. In the machine as shown in Fig. 4, switch 39e has just opened and has actuated the dispensing mechanism of chute 36e, the bag 35a being under the chute to receive the orange. As shown, bag 35a is approaching chute 36f, and after the pin 41a has passed the slide 40f the dispensing mechanism associated with chute 36f will function to deposit an orange in the bag. It will thus be understood that as a bag travels through the filling zone it receives one orange from each chute and the total number of oranges

deposited in each bag is determined by the number of operating chutes in the filling zone. This number is variable to suit the particular packing requirements.

One of the orange dispensing mechanisms, as shown in detail in Figs. 5 through 7, will now be described. In the outlet end of the chute there is rotatably mounted on a transverse shaft 42 a wheel having a hub 43 and four quadrantly arranged pairs of radially extending curved fingers 44. The hub 43 is positioned slightly below the rails 37 and the fingers 44 rotate through the slot between cooperating rails. In operation, the hub 43 and the fingers thereto affixed, are rotated through one-quarter of a revolution in a clockwise sense as seen in Fig. 5 for each actuation of the associated switch 39, thereby to feed one orange from the chute.

To accomplish this result, a ratchet wheel 45 having four teeth is integrally attached to the hub 43 and a dog 46, carried by the triangular dog-plate 47 pivoted on the shaft 42, cooperates with the ratchet wheel to rotate the latter. The dog 46 is pivotally mounted on the plate 47 by means of a screw 48 and the nose of the dog is resiliently urged into contact with the ratchet wheel 45 by a tension spring 49. A link 50 is pivoted at its upper end to the dog-plate at 51 and is pivotally attached at its lower end by a pin 52 to the core 53 of a solenoid 54. The link 50 has a stop bracket 55 that engages the tip of one of the fingers 44 when the link is in the raised position, as shown in full lines in Fig. 7, and releases the finger to permit rotation of the wheel when the link is lowered, as shown in dotted lines in Fig. 7. A compression spring 56 normally retains the solenoid core 53 in raised position.

In operation, the solenoid 54 is energized by the closing of its associated switch 39 and the core 53 is drawn down against the action of spring 56. The dog 46 moves from its full line position in Fig. 7 to the dotted line position to engage the next tooth of the ratchet wheel 42. Upon de-energization of the solenoid, the spring 56 returns the mechanism to the full line position and discharges an orange from the chute by causing the curved fingers 44 to rotate through one-quarter of a revolution. The operation is repeated as often as the switch controlling the solenoid is closed and opened.

Referring now to Figs. 8 and 9, the bag supporting device shown includes the cooperating elements 27 and 28, previously referred to. These elements are carried by the conveyor chain 26, the element 27 leading the element 28. Each of the elements 27 and 28 has a vertical shaft 57 journalled in bearings 58 included between brackets 59 forming upper and lower links of the chain 26. The upper ends 60 of the shafts 57 are bent horizontally as shown to form followers, the function of which will be set forth hereinafter.

The leading bag supporting element 27, as shown in detail in Figs. 10 through 13, has a horizontal cross-bar 61 secured to the lower end of shaft 57 by nuts 62 and 63. At what may be termed the inner or following end of the cross-bar, a depending finger or spreader bar 64 is pivoted on a pin 65. A spring 66 received in the recess 67 and carried by a support pin 68 has one end 69 bearing against the side of the spreader bar 64 and other end 70 bearing against a wall of the recess to urge the bar 64 in a clockwise direction as seen in Figs. 10 through 13. A stoppin 71 limits the clockwise rotation of the bar 64. The spreader bar carries a prong or pointed pin

72 near its lower end which penetrates the fabric of a bag at one of the corners thereof to support the bag at this position.

At the outer or leading edge of the cross-bar 61 another spreader bar 73 is pivoted on the pin 74. A spring 75, similar to the spring 66, presses against the inner face of the bar 73 to urge the latter outwardly in a counterclockwise direction as seen in Figs. 10 through 13 and a stop 76 limits the swing of the bar in that direction.

The spreader bar 73 is also provided with a bag retaining prong 77. Unlike the prong 72, which is fixed, the prong 77 is retractable into the body of the spreader bar. Prong 77 is formed on one end of a lever 78 pivoted at 79. The lever is received in a slot 80 recessed in the body of the spreader bar and the prong projects through a hole 81. A cam slot 82 is cut in the upper arm of the lever 78 and the loop 83 of the spring 75 is threaded through this slot. Following the inward or clockwise movement of the bar 73 through Figs. 10, 11, 12, and 13, it will be seen that, as the bar is moved, the spring loop 83 rides down the adjacent face of the bar 73 and downwardly through the slot 82 to rotate the lever 78 in a clockwise direction on its pivot 79 and to retract the prong 77 within the body of the bar. Reverse movement of the bar causes the prong to project through the hole 81.

Returning to Figs. 8 and 9, the bag supporting element 23 is similar to the element 27 described in detail hereinbefore. However, the prongs 84 and 85 are fixed, and the element has no retractable prong corresponding to the prong 77 of the element 27. The spreader bars 86 and 87 are pivoted to the cross-bar 88 and are biased apart by springs; the spreader bars may be pressed towards each other against the force of the springs.

The bag supporting elements 27 and 28 together provide a single bag supporting device to hold, for example, the bag 35c in Fig. 4. Bags are easily applied to the devices 27-28 at the bag-attaching station 29, the spreader bars yielding inwardly as the mouth of a bag is slipped thereover and pressing outwardly to distend the mouth of the bag and force the prongs through the fabric thereof.

As best shown in Fig. 5, the switch closing pins 41 carried by the leading bag supporting element 27 are so located with respect to the level of the switch operating slides 49 that they will close the switches only when a bag is in place and the spreader bar 64 is substantially perpendicular. When no bag is in place, the spreader bar 64 is swung outwardly by its spring to swing the end of the pin 41 above the level of the switch operating slides and thus to prevent closing of any of the switches 49 by a bag supporting device on which a bag, through inadvertence, may not have been hung. Such arrangement eliminates the feeding of fruit to a conveyor position having no bag in place to receive the fruit.

Referring back to Fig. 1, the bagging machine has a slotted track 89 that parallels the conveyor chain and extends from an entrance 90, just beyond the bag-removing station 34 in the direction of conveyor travel to an exit 91 at the start of the bag-closing zone 31. The horizontal followers 60 of the bag supporting devices 27-28 are engaged in the slotted track to maintain the elements 27 and 28 in parallel alignment perpendicular to the direction of travel throughout the length of the track. The followers 60 are released in the zone between the track exit 91 and

the track entrance 90 to permit the bag supporting elements to be turned on their shafts 57. It will be seen that bags carried by the bag supporting devices are held open from the bag attaching station 29 through the bag filling station, as is desired.

In the bag-closing zone 31, there is located a turning plate 92. The plate is supported by the framework at the level of the cross-bars 61 and 10 88 of the bag-supporting elements 27 and 28; it is inclined in the direction of conveyor travel from the line of travel of the inner ends of the cross-bars when they are perpendicular to the line of travel to the line of travel of the inner edges of 15 the cross-bars when they are oriented parallel to the line of travel. As the bag-supporting devices move through the bag-closing zone, the inner ends of the cross-bars engage the turning plate 92 and the elements 27 and 28 are turned through 20 90° to bring them parallel to the line of travel and to close the mouths of bags supported thereon as shown in Fig. 1.

The closed bags are presented edgewise to the sewing machine 32, as best seen in Fig. 2, and 25 the tops are sewn closed. As shown, the sewing machine is driven by an electric motor 93 through a belt drive 94.

With certain types of sewing machines, the stitching continues across the gaps between adjacent bags forming a cord uniting the bags. In 30 order to separate the bags the connecting cord must be cut. To accomplish this, there is provided the knife 33 slidable in the solenoid 95 and operated by energization and de-energization of the solenoid to move in and out and cut the connecting cord.

Filled and sewn bags are automatically removed from the bag supporting devices at the bag removal station 34. At this station, an arm 40 96, secured to the frame, projects into the path of travel of the bags at about the level of the top closure seam line. The arm has a bumper 97 against which the leading edges of the bags hit, as best seen in Fig. 3.

45 When the leading edge of the bag 35d hits the bumper 97, the spreader bar 73 is pivoted rearwardly and the retractable prong 77 is withdrawn inside the body of the spreader bar, thus releasing the leading edge of the bag.

50 It will be noted that the prong 72 on the spreader bar 64 and the prong 85 on the spreader bar 87 both project upwardly and rearwardly as oriented on the leading bag 35d in Fig. 3. It will also be noted that the prong 84 on the spreader bar 86 projects upwardly and directly to the rear. 55 As forward movement of the conveyor continues, the pressure on the bag 35d causes the bag to ride up and rearwardly off of the prongs 72, 85 and 84. When the bag is free of the supporting prongs, it falls into the chute 98 from which it may be removed in condition for shipment. The bags generally employed are of the conventional open-mesh type and are retained by the prongs without damage.

60 In Fig. 14 there is shown an alternative fruit dispensing mechanism that releases the fruit two at a time and feeds it into the bags. In this figure, reference numerals identical with numerals employed in preceding figures are used to designate corresponding parts. 65 Positioned near the outlet end of the orange chute 36 is a gate 99 carried by a lever 100 pivoted to the frame by a pivot 101. At the end of the lever 100 opposite to the end carrying the gate 99 is a stop plunger 102 slidably received in

70

a hole in the lever arm and urged downwardly by a spring 103. The lever is normally biased to the full-line position shown in Fig. 14 by a spring 104 hooked to the end of the lever 100 and to the frame.

A solenoid 105 having a core 106 is mounted on the frame, the core being connected by an articulated link 107 to the lever 100. On energization of the solenoid, the core 106 is drawn downwardly and the mechanism is rocked to the dotted-line position. With the mechanism in this position, the oranges 38a and 38b roll from the chute into the awaiting bag 35. The oranges 38c and 38d are held in position and restrained from rolling out of the chute by the yielding stop plunger 102. Upon return of the parts to their full-line position under the influence of spring 104 after the solenoid is de-energized, the oranges 38c and 38d roll into the forward position adjacent to the gate 99 and are ready to be released upon the next cycle of operation.

Referring to Figs. 15 through 18, there is shown in pertinent part a modification of the bagging machine including alternative forms of bag supporting device and mechanical means for actuating the article dispensing mechanism. The section plane of Fig. 15 extends through the track 89' in the bag-filling zone of the machine adjacent to the article chutes.

In Fig. 15, the frame 108 supports the endless chain 26' in a guideway or track 109. Brackets 59' on the chain and the bearing 58' included therebetween journal the shaft 57' of a bag holding element 27'. A follower 60' at the upper end of the shaft 57' retains the bag holding element 27' in its bearing and also, by engagement with the sides of the track 89', which extend from the point 90 to the point 91, as seen in Fig. 1, maintains the element 27' oriented with its cross-bar 88' perpendicular to the direction of conveyor travel.

As best seen in Figs. 17 and 18, the cross-bar 88' is provided with integral or fixed depending legs 110 having spring clips 111 affixed to their outer surfaces by means of rivets 112 and screws 112'. The spring clips extend somewhat below the lower ends of the legs 110. They and the legs are provided with aligned holes 113 through which pins 114 pass. These pins are somewhat flexible and are joined to a hub 115 carried by a rod 116 extending longitudinally through an axial hole formed in the shaft 57' and terminating in a button 117 projecting above the top of the follower 60'.

From the lower end of the hub 115, a guide rod 118 depends and passes through a hole in the guide bracket 119. A spring 120 is compressed between the guide bracket and hub to normally urge the hub upwardly.

As shown in Fig. 17, the hub is raised to its uppermost position engaging the under surface of the cross-bar 88' as a stop. The pins 114 are of such a length that the lower ends thereof are withdrawn into the holes in the legs 110 when the hub is raised. With the pins in this position, the lip of a bag may be inserted between the spring clips 111 and the adjacent surfaces of the legs 110 and pulled up so that the pins, when extended, will pass through the walls of the bag and retain it securely on the holder. The spring clips exert sufficient gripping action to support an empty bag.

The pins 114 are shown projecting through the holes 113 in Fig. 15. It will be seen that downward movement of the button 117 will de-

press the rod 116 and cause the pins to be projected outwardly to pierce the walls of a bag and hold it securely in place. The button 117 is depressed by engagement with the top of the track 89' and is held in depressed position as the conveyor travels from a point just beyond the bag attaching station, through the bag filling, closing, sewing and severing stations. At the bag removal station, the top portion of the track is omitted; when the bag supporting elements reach the bag removal station, the springs 120 withdraw the pins 114 into the position shown in Fig. 17 allowing the filled bag to drop from the supports.

15 It will be understood that a pair of adjacent bag supporting elements 27' and 28' cooperate to support the four corners of the open mouth of a bag in the manner of the devices shown in Figs. 8 and 9 and that bag closing is effected by a turning cam such as the cam 92 shown in Fig. 1. It will also be understood that the bumper 97 is dispensed with when the modified bag holders are used.

20 The mechanical tripping arrangement is illustrated in Figs. 15 and 16. In this arrangement, a link 121 is operatively connected to an article dispensing device such as either of the devices of Figs. 7 or 14. The link 121 may be pivotally connected at its lower end to the point 51 of the 25 device of Fig. 7, or it may be connected in the device of Fig. 14 as is the link 107 to the rocking lever 100.

25 At its upper end, the link 121 is pivoted at 122 to a lever 123 that rocks on a pin 124 carried by the frame 108. The other end of the lever 123 is connected through a universal joint 125 to a connecting rod 126, which in turn has a universal joint 127 coupling it to a follower 128 pivoted to the frame on a stub shaft 129. The pin on which 30 the lever 123 rocks is supported on the frame by a bracket having a slot and bolt connection 124' providing vertical adjustability for the pivot pin 124.

35 The link 121 is normally urged upwardly by a spring 130 tensioned between the pivot 122 and an arm 131 fixed to the frame 108 and is moved downwardly by rocking the follower 128 in a 40 counterclockwise direction as seen in Fig. 16.

45 Such rocking movement is accomplished by the 50 horizontal movement of a bag supporting element 27' which carries a cam roller 132 that rolls along the under surface of the follower to raise the latter as the bag supporting element passes by. Movement of the bag supporting element 55 is from left to right as seen in Fig. 16, and it will be observed that when the roller 132 passes beyond the lower end of the follower 128, the follower and its linkage assembly will return to normal position under the urging of the spring 130.

60 Although the connecting rod 126 may take the form of a rigid bar, it is shown as a composite, spring-biased bar including a cylindrical section 133 in which a sliding piston section 134 is 65 fitted. The piston has a notch 135 loosely embracing a pin 136 carried by the cylindrical section 133, and the piston may slide in the cylinder within limits imposed by the dimensions of the slot. A spring 137 is compressed between the upper end of the cylinder and the head of the piston and urges the piston towards its lowermost position with respect to the cylinder. Such composite bar construction affords a cushioning effect minimizing shock upon initial impact of a 70 cam roller 132 with the follower 128.

One complete cycle of the cam follower 128 results in the dispensing of one piece of fruit from a chute in the bag-filling zone. It will be understood from the description of the filling operation given in connection with Fig. 4 that only one cam roller 132 is provided for each co-acting pair 27'-28' of bag supporting elements and that each article dispensing chute in the filling zone has associated with it one of the mechanical linkage systems just described. It will also be appreciated that the assembly in the filling zone is so constructed and arranged that when the fruit or other articles are dispensed from the chutes, the bags carried by the conveyor are in position to receive it.

While there have been disclosed devices for feeding fruit or other articles from the chutes into the bags, which operate on the counting principle, it will be understood that other types of feeders, such as those which dispense in accordance with weight or volume of the articles to be fed, may be employed without departing from the invention. Also, the filled and sewn bags may be removed from the bag supporting devices by hand or by other means.

From the foregoing description it will be seen that the present invention provides a machine for bagging articles such as citrus fruit and the like that greatly decreases labor requirements in the packaging of such articles for sale and shipment. The machine is largely automatic and a single skillful operator can tend one machine having a large daily output.

I claim:

1. In a bagging machine, an endless conveyor; means for driving said conveyor; bag supporting devices carried by said conveyor, each of said bag supporting devices comprising a pair of brackets spaced longitudinally in the direction of travel of the conveyor and pivotally mounted for horizontal swinging movements, a pair of spaced fingers depending from each of said brackets, means on said fingers for holding a bag thereon, whereby, when said pairs of fingers are swung transversely of their direction of travel the mouth of a bag carried by a supporting device is held open and when said fingers are swung parallel to their direction of travel the mouth of such bag is held substantially closed; a stationary track section extending along the direction of travel of said conveyor; a follower carried by each of said spaced brackets, said follower engaging said track and being constructed and arranged to maintain said bracket in such position that the spaced fingers are disposed transversely to the direction of travel of said conveyor; and a stationary cam positioned to be engaged successively by said pivoted bracket and finger assemblies at a location in which the followers are disengaged from said track section and to swing them to positions in which said spaced fingers are disposed substantially parallel to the direction of travel of said conveyor.

2. In a bagging machine including a bag-attaching station, a bag-filling station and a bag-closing station, an endless conveyor; means for driving said conveyor; bag supporting devices carried by said conveyor, each of said devices comprising a pair of horizontal arms spaced longitudinally of the direction of travel of the conveyor and pivotally mounted for horizontal swinging movements, a pair of fingers depending from each of said arms and being pivotally mounted thereon for swinging movements about a horizontal axis, means biasing the fingers of each pair

of fingers away from each other, and an outwardly pointing pin affixed to the lower end of each finger for piercing a bag engaging said fingers, whereby, when said arms are positioned transversely of their direction of travel the mouth of a bag carried by an supporting device is held open and when said arms are positioned parallel to their direction of travel the mouth of such bag is held substantially closed; a stationary track 10 extending along the direction of travel of said conveyor from said bag-attaching station to said bag-filling station; a follower carried by each of the horizontal arms of said bag filling devices, engaging said track, and constructed and arranged to maintain said arms in transverse relation to the direction of travel of said conveyor; and a stationary cam positioned at said bag closing station to engage the ends of said horizontal arms and swing them to a position parallel to the direction of travel of said conveyor.

3. For use with a moving conveyor, a bag holding device comprising a leading element and a following element spaced apart in the direction of travel of the conveyor; said leading element 25 including a horizontal bar mounted for rotation in a horizontal plane, depending fingers pivotally carried by the ends of said bar, spring means urging said fingers outwardly apart, an outwardly pointing fixed pin carried by one of said fingers, an outwardly pointing movably mounted pin carried by the other of said fingers, and means actuated by inward movement of said other finger for retracting said second pin within the body 30 of said other finger and by outward movement of said other finger for projecting said second pin from the body of said other finger; said following element including a horizontal bar mounted for rotation in a horizontal plane, depending fingers pivotally carried by the ends of said bar, spring means urging said fingers outwardly apart, and outwardly pointing fixed pins carried by each 35 of said fingers.

4. In a bagging machine, a horizontally disposed conveyor, means for driving said conveyor, and a bag supporting device carried by said conveyor comprising a pair of bag supporting elements dependingly mounted on said conveyor for rotation about vertical axes, each of said elements having a pair of spaced leg members, means on said leg members adjacent to the lower ends thereof for holding a portion of the lip of a bag, said bag supporting elements being so spaced on said conveyor that said bag lip holding means define a substantially quadrangular figure when said bag supporting elements are disposed transversely of the direction of travel of said conveyor and define two lines parallel to the line of travel of said conveyor when said bag supporting elements are rotated to a position parallel to the direction of travel of said conveyor.

5. In a bagging machine, a horizontally disposed conveyor, means for driving said conveyor, a bag supporting device carried by said conveyor comprising a pair of bag supporting elements dependingly mounted on said conveyor for rotation about vertical axes, each of said elements having a pair of spaced leg members, means on said leg members adjacent to the lower ends thereof for holding a portion of the lip of a bag, said bag supporting elements being so spaced on said conveyor that said bag lip holding means define a substantially quadrangular figure when said bag supporting elements are disposed transversely of the direction of travel of said conveyor and define two lines parallel to the line of travel of

11

said conveyor when said bag supporting elements are rotated to a position parallel to the direction of travel of said conveyor, and successively arranged in the direction of travel of said conveyor; means actuated by engagement with said bag supporting device for introducing articles into a bag carried by said device, and means engaging said bag supporting elements to align them parallel to the direction of travel of said conveyor.

6. For use in a bagging machine, a bag supporting device comprising a pair of bag supporting elements, each element comprising a shaft adapted to be rotatably mounted on the conveyor of a bagging machine, a yoke mounted on one end of said shaft and having a pair of spaced legs extending from said shaft, spring clip means mounted on each of said legs for yieldingly gripping a portion of the lip of a bag between the clip and the leg, each leg and associated clip having

5

12

aligned holes, a pin slidably mounted in the hole of each leg, and means for sliding said pin between a position in which it is retracted within the hole in said leg and a position in which it projects through the hole in said clip.

CECIL DANIEL HUGHES.
